CHAMPAGNE BOTTLE STOPPER

Floyd A. Terwilliger, Rochester, N. Y.

Application March 22, 1955, Serial No. 35,162

Term of patent 14 years

(Cl. D58—26)

FIG. 1.

FIG. 2.

FIG. 3.

FIG. 4.

Fig. 1 is a side elevation of a champagne bottle stopper embodying my new design;

Fig. 2 is an axial section therethrough;

Fig. 3 is a top plan view thereof; and

Fig. 4 is a bottom view thereof.

I claim:

The ornamental design for a champagne bottle stopper, substantially as shown.
